UNITED STATES PATENT OFFICE.

STANLEY W. NICHOLSON, OF TOLEDO, OHIO, ASSIGNOR TO THE DURA COMPANY, OF TOLEDO, OHIO, A CORPORATION OF DELAWARE.

WINDOW-CONTROL MECHANISM.

Application filed May 22, 1922. Serial No. 562,870.

To all whom it may concern:

Be it known that I, STANLEY W. NICHOLSON, a citizen of the United States of America, residing at Toledo, in the county of 5 Lucas and State of Ohio, have invented certain new and useful Improvements in Window-Control Mechanism, of which the following is a specification, reference being had therein to the accompanying drawings.

10 This invention relates to window control mechanism and relates more particularly to control mechanisms for the sliding windows of vehicles.

15 The invention consists in the structural features and arrangement of parts herein-after fully described and illustrated in the accompanying drawings wherein:

20 Figure 1 is an interior view of a motor vehicle door equipped with the improved control mechanism;

Figure 2 is a cross section on line 2—2 of Figure 1;

25 Figure 3 is a fragmentary perspective view of the actuating and latch elements for said mechanism.

30 In these views the reference character A designates an automobile door formed in its upper portion with a window opening B provided with a vertically sliding closure C having the nature of a glass plate. In opening the window, said plate is adapted to be lowered into a well or chamber D formed in the lower portion of said door. F is a counterbalance arm for the sliding plate C, said arm being pivoted at one end upon a 35 upright A' of the door, as indicated at F', and carrying at its other or free end a roller F² which is caused to bear constantly upon the lower edge of the closure C by a coiled 40 spring G exerting an upward effort upon said arm. For actuating the closure C there is provided a control rod H vertically extending adjacent the upright A' and bent at its upper extremity to form a handle H', the lower end of said rod being attached to 45 said closure adjacent the lower edge of the latter. Said rod is upwardly extended a sufficient distance to render the handle H' accessible, even when the closure is in its lowermost position. It is desired to utilize the rod H to control latching of the plate C, as well as to actuate vertical movement of the latter and to this end said rod is 50 rotatively engaged with the closure. Thus the channel member I which embraces the bot-

tom edge of the plate C (as is common practice) is formed at one end with a laterally extended tongue I' which is terminally fashioned to form a bearing I² wherein the lower end portion of the rod H is journaled. Within the well D there is secured to the upright A', by screws I³, a vertically elongated latch plate J having an edge portion extending in back of the rod H and formed with a series of notches J'. The rod H projects slightly below the journal bearing I² and is terminally bent and flattened, as indicated at K, to form a latch element which through rotation of said rod is engageable in any of the notches J'. L is a spring coiled upon the 60 rod H between the bearing I² and element K and rotatively urging the rod into latch engagement with the plate J, as is clearly shown in Figure 3. Normally the handle H' projects at an acute inclination to the plate C, as shown in full lines in Figure 2 and in dash lines in the same figure is indicated the position of said handle corresponding to the released position of the latch element K (also shown in dash lines). It is preferred 65 to vertically groove the member A' within the well D in back of the notched edge portion of the plate J, as shown at M, to provide the necessary clearance for rocking and vertical travel of the element K.

70 Within the window opening B a tubular metal trim stick N is secured to the upright A' and it is preferred to locate the control rod H within said trim stick, the latter being vertically slotted, as indicated at N', to permit the handle H' to project and to undergo the necessary vertical and annular movements. Preferably the edges of said trim stick, marginal to the slot N', are beaded 75 interiorly of the trim stick, as indicated at N², for the purpose of reinforcing the trim stick. As is best seen in Figure 2 the slotted edge portion of the plate J lies directly beneath the trim stick N in order to establish the necessary coaction with the latch element K. Said figure also best discloses the employment of the plate J as a seat or backing for the felt slideway O which marginally engages the plate C.

80 One of the main advantages which is secured by the described construction is the complete concealment of the latch means within the well D, as well as a substantial concealment of the control rod H within the tubular trim stick N. The described latch 85

means, while of a very simple nature, suffices to securely maintain a sliding closure in any of a large number of selective positions of adjustment.

5. What I claim as my invention is:—

1. In a window control mechanism the combination with a sliding window closure and a chamber receiving said closure in window opening positions thereof, of a latch plate extending within said chamber in the direction of movement of said closure, a coacting latch element and a rotative control member for said latch element projecting into the window opening in all positions of said closure.

10. 2. In a window control mechanism the combination with a sliding closure for a window opening, of a chamber receiving said closure in the window opening positions thereof, an elongated latch plate extending within said chamber in the direction of movement of said closure, a coacting rotative latch element and control means for said element accessible within the window opening in all positions of the closure.

15. 3. In a window control mechanism the combination with a sliding closure for a window opening, of a chamber receiving said closure in the window opening positions thereof, an elongated latch plate extending within said chamber in the direction of movement of the window member, a coacting rotative latch element carried by said closure and a control rod mounted upon said closure for actuating the same projecting into said window opening in all positions of the closure and rotative to actuate said latch element.

20. 4. In a window control mechanism a slide-40 able window member, a chamber receiving said member in its open positions, a latch member within said chamber elongated in the direction of travel of the window member, a latch element upon the window member coacting with said latch member, and a rod mounted upon the window member controlling sliding thereof and rockable to additionally control said latch element.

25. 5. In a window control mechanism, a vertically slideable window closure, a vertically elongated latch member downwardly extending from the window opening, a control rod rotatably mounted upon the closure, and a latch element carried by said closure adjacent the lower edge thereof coacting with the elongated latch member to hold

the closure adjusted and controlled rotatively by said rod.

6. In a window control mechanism, the combination with a slideable window member, a rod rotatively extending upon said member in the direction of travel thereof, a latch element upon one end portion of said rod, coacting stationary latch means, and a handle upon the other end portion of said rod controlling travel of said window member by subjection of the rod to longitudinal stress, and controlling said latch element through rotation of the rod.

7. In a window control mechanism, a slideable window member, a chamber receiving said member in open positions thereof, a fixed latch member located substantially in its entirety within said chamber, a coacting latch element carried by the window member, and a member carried by the window member actuating sliding thereof and rotative to control said latch element.

8. In a window control mechanism, a slideable window member, a control rod rotatively mounted upon said window member and extending parallel to the direction of travel thereof, and an actuating handle and latch element mounted fast respectively upon the extremities of said rod.

9. In a window control mechanism, the combination with a sliding closure for a window opening, of a chamber receiving said closure in the window opening position thereof, an elongated latch plate extending within said chamber in the direction of movement of said closure, a coacting latch element rotative upon an axis parallel to the direction of movement of said closure, and control means for said rotative element accessible within the window opening in all positions of the closure.

10. In a window control mechanism, the combination with a slideable window member, of a control rod extending upon said member in the direction of travel thereof, said rod having a transversely bent portion at one extremity forming a latch element and a transversely bent portion at the other extremity and spaced longitudinally of said rod from said first-mentioned transversely bent portion and forming a handle, and stationary latch means engageable by said first-mentioned transversely bent portion.

In testimony whereof I affix my signature.

STANLEY W. NICHOLSON.
